UNITED STATES PATENT OFFICE

2,317,314

MOTOR-DRIVEN BRUSH

Egbert Van Haafoten, Lancaster, Pa.

Application October 15, 1940, Serial No. 361,326

3 Claims. (Cl. 15—28)

The present invention relates to motor driven brushes, and more particularly to a motor driven tooth brush in which the bristle carrying member is mounted for rotation and is adapted to be driven by an electric or other motor enclosed within a casing constituting a handle member.

The principal object of the present invention is the provision, in a motor driven brush of the type in question, of a "head" assembly of extremely simple design and economical manufacture, in which the bristle carrier is readily detachable and replaceable.

A further object is the provision of a head assembly in which the rotating parts are mounted in simple bearings of relatively large bearing surface area, thus dispensing with the use of balls, rollers, or other anti-friction elements, and requiring no lubrication other than the water ordinarily employed when brushing the teeth.

A further object is the provision of a head assembly which may be taken down with the utmost ease for cleaning or other purposes, and without the necessity of removing any screws or other like fastening means.

Other and further objects, features, and advantages of the present invention will be apparent to one skilled in the art from the following description taken in connection with the accompanying drawing, in which:

Figure 1 is an assembly view, partly in elevation and partly in section, of a complete unit constructed in accordance with the present invention;

Figure 2 is a section on line 2—2 of Figure 1;

Figure 3 is a rear elevation of the bristle carrier according to the present invention;

Figure 4 is a front elevation of the ring gear to which the bristle carrier is adapted to be detachably secured; and

Figure 5 is a fragmentary section illustrating the means employed for sealing the motor casing against entrance of moisture.

In order to facilitate an understanding of the invention, reference is made to the embodiments thereof shown in the accompanying drawing and detailed descriptive language is employed. It will nevertheless be understood that no limitation of the invention is thereby intended and that various changes and alterations are contemplated such as would ordinarily occur to one skilled in the art to which the invention relates.

Referring to the drawing, the device of the present invention comprises generally an electric motor 10 of any suitable and conventional type, preferably universal, enclosed within a casing 11.

which may suitably be made in two complementary parts formed of a synthetic plastic material. The motor 10 may be supplied with electric energy from any suitable source through the usual two-conductor cable 12.

In order to prevent the admission of moisture to the interior of the casing 11, the complementary halves 11a and 11b thereof are formed with peripheral semi-cylindrical grooves, as seen in Figure 5, and a cylindrical resilient sealing member 11c, of rubber or similar material, is cemented into one of such grooves. The casing members 11a and 11b are secured together, with the sealing member 11c clamped tightly therebetween, by screws or other suitable means.

The shaft 13 of the motor 10 extends outwardly of the forward end of the casing 11 and is supported in a sleeve bearing 14 of conventional design. The projecting portion of the shaft 13 is enclosed within a tubular casing 15, and is provided at its distal end with a pinion 13' (Figure 2) which may suitably be formed integral with the shaft 13. The tubular casing 15 may be removably secured to the casing 11 in any suitable manner, such as by a bayonet joint or spring catch and is formed at its outer end to provide a circular eye 16, the inner surface of which provides the bearing surface for the rotating parts of the brush head assembly.

Referring to Figure 2, it will be seen that the inner surface 16' of the eye 16 is recessed adjacent one edge thereof to provide an annular bearing surface 17 and a shoulder 18. A ring gear 19 is rotatably mounted within the bearing surface 17 and is provided with a peripheral flange 20 which slidably engages the adjacent edge of the eye 16, the teeth of the ring gear 19 meshing with those of the pinion 13'. A bristle carrier 21 is rotatably mounted within the eye 16 and loosely engages the inner surface 16' thereof. The bristle carrier 21 is provided with a peripheral flange 22 adapted to rotate in loose contact with the adjacent edge of the eye 16.

The ring gear 19 is provided at its inner edge with an annular groove 23, and the central boss 24 of the bristle carrier 21 is similarly provided with an annular groove 25 in which is seated a resilient split washer 26. The outer or rearward surface of the boss 24 is slightly bulged, as seen in Figure 2, and it will be readily apparent that the bristle carrier 21 may be detached from the ring gear 19 by merely pressing upon the bulged surface of the boss 24. When this is done, both the bristle carrier 21 and the ring gear 19 may be readily lifted out of engagement with the eye 16.

It will be understood that the tufts of bristles 27 are secured in the bristle carrier 21 in any suitable manner, the details of which form no part of the present invention.

From the foregoing description it will be apparent that an extremely simple assembly is provided, in which the bristle carrier is readily detachable and may be easily replaced, at small cost, when the bristles become worn or otherwise unsuitable for use. Similarly, the bristle carrier and ring gear may be very easily removed from the assembly for cleaning or any other purpose. The entire head assembly is extremely convenient and economical to manufacture.

While it is preferred to employ metal for the tubular casing 15, ring gear 19, and bristle carrier 21, it will be understood that any other suitable material may be employed, such as a synthetic plastic, compressed fiber, or the like.

Having thus described the invention, what is claimed as new and desired to be secured by Letters Patent is:

1. In a motor-driven brush, a shaft, motor means for rotating said shaft, a tubular casing enclosing said shaft and formed at one end with a circular eye providing an annular bearing, a ring gear mounted in said bearing, said ring gear

having a peripheral flange overlying one edge of said eye, toothed means carried on the adjacent end of said shaft and meshing with said ring gear, and a bristle carrier extending through said eye and ring gear and detachably secured to said ring gear, said bristle carrier having a peripheral flange adapted to overlie the edge of said eye opposite to said ring gear, whereby said gear and carrier are maintained in place relative to said eye.

5 2. Device according to claim 1, said ring gear being provided with an internal annular groove, and said bristle carrier having resilient means associated therewith for detachably engaging in said groove.

10 3. In a motor driven brush, a brush supporting eye providing an annular bearing, an assembly mounted in said bearing and comprising a bristle carrier and a ring gear separably joined through a resilient snap connection, said carrier and gear each having a flange overlying at least a portion of the body of said eye on opposite-sides thereof whereby said assembly is restrained from any substantial movement through said eye, and means for rotating said ring gear.

EGBERT VAN HAAFTEN.
